UNITED STATES PATENT OFFICE.

JOHN P. KRIEGL, OF MILWAUKEE, WISCONSIN.

ANGLE FLOAT.

Application filed September 27, 1926. Serial No. 137,931.

My invention relates to tools for plasterers' use in plastering houses, and the like purpose, and is specially designed for use in the angles where the side walls join, or where the ceiling and side walls join in the angle at the ceiling. In the past it has been the practice to finish off each side separately, and in finishing one side, there is always the danger of disturbing another finished 10 side by scraping or dragging the tool against such other side.

The object of my invention is to provide a tool which will finish up the angle, removing any excess of mortar, and one which will 15 finish the two adjoining walls at the same time, thereby doing double duty, and overcoming any danger of injury to one wall while the other is being finished.

With the above and other objects in view, 20 which will more particularly appear in the following specification, I have shown and described herein one embodiment of my said invention, but do not wish to be confined to the identical form and construction shown 25 herein, as it may be widely varied to meet different requirements, without departing from the spirit of my invention. In the accompanying illustrations, in which like numerals of reference indicate the same 30 parts throughout the various views,

Figure 1 is a perspective view of one of my angle floats.

Figure 2 is a cross section taken along the line $x-x$ in Figure 1.

Figure 3 is a cross section taken along the line $y-y$ of Figure 1.

Figure 4 is a side view of my angle float.

In the accompanying drawings, I have shown one embodiment of my invention for 40 use by plasterers for finishing in the angles on plastered walls, where all of the angles are right angles. While the body portion may be of any suitable material, I have shown one in which the body portion 1 is 45 made of wood, with a handle 2 attached at the top for holding it while in use. The two working sides 3 and 4 in the float shown, are at right angles for finishing in right angle corners, as most of the angles in 50 building construction are made to meet at right angles. At the edge 5 where the two sides 3 and 4 meet I have attached the removable metal piece 6. This metal piece 55 has its edge beveled to conform to the angle formed by the two sides 3 and 4, and its body portion may be of any suitable size

and shape, and may be attached to said body portion 1 by means of rivets, pins, screws or other suitable means. This metal piece 6 has the advantage of wearing more slowly 60 than the wood and forms a sharp exact angle and retains it for a considerable length of time. At any time that it becomes worn so that it does not give satisfactory results, it may be removed, and a new strip 65 inserted to take its place.

At one end of my float, as at 7, I have preferably rounded off the working sides 3 and 4 where they form an edge in meeting the said end 7, and by this construction, I 70 find that the wall may be finished without the float leaving any marks, or scoring or dragging effects as is done when the end has the sides exactly at right angles as would be the case if these portions were not cut away 75 to form the shape herein shown.

At the end 8 I have cut away the middle and upper portions of the end, as shown, forming two faces 9 and 10 which meet the working sides 3 and 4 at an acute angle at 80 11 and 12, and which form a sharp point where these edges meet the working edge formed between sides 3 and 4, at the point 13. I have preferably covered this end 8 with metal of suitable thickness to protect 85 it from wear, as 14. This metal has the added advantage of forming sharper angles at the edges 11 and 12, and at the point 13 than could well be formed with wood, and the metal retains such sharp edges for a 90 longer time. This metal cover is preferably attached by means of screws, or other means of attachment which will permit it to be removed and replaced by another piece in case it should become worn sufficiently to 95 require such repair.

While I have shown my float as constructed of wood with its edges protected by removable metal portions, it will be apparent that said float may be constructed entirely of metal if desired, either solid, or hollow, and that said float, if built in the shape shown by me, will do the work equally well. Although the float which I have shown has its working sides 3 and 4 at an angle of 90° , it will be apparent that special floats may be constructed with less or greater angle, to finish in corners where the angle between the walls is less or greater than the 90° angle found most frequently in 105 building construction.

In use I find that my float will readily

and quickly finish both walls where two walls meet, and leave it perfectly smooth, with a clean sharp corner. Where the three walls meet at the ceiling, the end 8 is used 5 to clean up the corner, and I find that this easily and quickly removes all surplus mortar, and finishes the corner smoothly and quickly, two walls at a time, and leaves the corner clean and sharp. Thus my float has 10 the advantage of finishing two sides at a time, where it has been customary to finish each side separately, and therefore my tool does the work much more rapidly, and I find it does it better, also by leaving the 15 corners sharp, it permits the finishing coat to be finished sharp in the corners without danger of the first coat showing through, as would be the case if the corners were filled up partially or rounded, instead of being 20 clean and sharp.

Having thus described my invention, what I claim, and desire to secure by Letters Patent, is the following:—

1. In a tool for plasterers' use, an angle 25 float having two operating sides at the required angle, with the sides rounded off at one end, the reverse end being recessed and a metal insert removably fitted in the recessed end, substantially as shown and de- 30 scribed.
2. In a device of the class described, an angle float consisting of a body portion having two operating sides at the required angle, a removable insert along the edge 35 where the two sides meet having its outer edge beveled to conform to the angles of said operating sides and a handle attached at the top, substantially as shown and de- scribed.
3. In a device of the class described an

angle float consisting of a body portion substantially triangular in cross section having two operating sides at the required angle, a removable insert at the edge where these two sides meet and having its outer edge 45 beveled to conform to the angles of said operating sides, the body portion having a recess at one end forming acute angles with the operating sides, and a handle attached on the third side, substantially as shown and 50 described.

4. An angle float for plasterers' use, having the body portion cut away at one end to form acute angles at the edges where the ends meet the operating sides substantially 55 as shown and described.

5. An angle float having one end cut away to form acute angles at the edges and point where the ends meet the sides, and the sides cut away to round off the edges where the 60 sides meet the reverse end, substantially as shown and described.

6. An angle float having one end cut away to form acute angles where the ends meet the sides, a removable plate covering said 65 end, and a removable insert at the edge where the two working sides join, substantially as shown and described.

7. An angle float for plasterers' use, having two working sides disposed at the re- 70 quired angle, a metal insert at the edge where the two sides meet, one end cut away to form acute angles where the ends meet the sides, a metal cover for said end, the sides at the reverse end being rounded off as 75 shown.

In testimony whereof, I have duly signed the foregoing specification.

JOHN P. KRIEGL.
